W. C. COLEMAN

CENTRIFUGAL MACHINE

Filed June 9, 1923

UNITED STATES PATENT OFFICE.

WILLIAM C. COLEMAN, OF WICHITA, KANSAS.

CENTRIFUGAL MACHINE.

Application filed June 9, 1923. Serial No. 644,346.

To all whom it may concern:

Be it known that I, WILLIAM C. COLEMAN, a citizen of the United States, residing at Wichita, in the county of Sedgwick and State of Kansas, have invented certain new and useful Improvements in Centrifugal Machines; and I do declare the following to be a full, clear, and exact description of the invention, such as will enable others skilled in the art to which it appertains to make and use the same, reference being had to the accompanying drawings and to the figures of reference marked thereon, which form a part of this specification.

This invention relates to centrifugal separators or amalgamators and the primary object of the invention is to provide a separator or amalgamator in which metal bearing ores may be introduced in a pulp or sludge form and flowed over the surface of a body of mercury so that the mercury can abstract or separate out the metal and allow the earth to pass out through the separator.

This particular invention contemplates the provision of means for subjecting the sludge or pulp to a prolonged action of the mercury so as to provide a time element or period of treatment long enough to take out practically all of the metal before the sludge is discharged.

The invention is shown as comprising two rotors, one within the other. One is the mercury-carrying rotor and the other is a distributor for distributing the sludge or pulp over the surface of the mercury. The sludge or pulp passes through the distributor in a tortuous path having recurring contact with the mercury so that it can be acted upon a number of times while it is in the machine.

The novel construction of my invention will be apparent by reference to the following description in connection with the accompanying drawings, in which—

Fig. 1 is a vertical, longitudinal, sectional view through a separator constructed in accordance with my invention.

Fig. 2 is a similar view of a slightly modified form, and

Fig. 3 is a fragmentary, cross sectional view through a slightly modified form of outer rotor.

The construction shown in Fig. 1 comprises an outer rotor 1 and an inner rotor

2. The outer rotor includes a casing having a top or removable cover 3, which may be fastened to the end of the hollow shaft 4, the hollow shaft being rotated by any suitable means. The bottom 5 of the outer rotor 60 is provided with a central opening 6 surrounded by an upstanding elongated tube 7 on which are radial impeller blades or vanes 8. A hollow distributor is located within the casing 1 and it constitutes the inner 65 rotor. It is shown as comprising a disk 9 connected to a shaft 10 by a spider 11, on the end of which is a collar 12 which may be fastened to the shaft 10. The shaft 10 is within the shaft 4 and it is adapted to be 70 rotated by suitable means.

There is a circumferential, depending wall 13 on the disk 9 and it carries a plurality of horizontal partitions or flanges 14 and 15 in spaced relation. The flanges or 75 ribs 14 are solid in cross section whereas the partitions 15 have ports or openings 16. The ported partitions 15 extend beyond the partitions 14 and their edges are designed to approximately contact with the ring-shaped body of mercury 17 in the metal absorbing tank 18 adjacent to the inner face of the circular wall of the rotor 1. Since the partitions 15 extend beyond the partitions 14, it will be apparent that the combined partitions and the wall of mercury 80 form a tortuous passageway for the pulp or sludge which is introduced into the machine through the tubular shaft 10.

When the metal bearing sludge or pulp 90 passes from the hollow shaft 10, it will flow through the openings 19 between the arms of the spider 11, over the disk 9 and through the tortuous passageway formed by the partitions 14 and 15 and the mercury so that 95 it will be subjected to a plurality of mercury actions; that is, the sludge or pulp will first come into contact with the mercury at the upper part of the rotor 1, then it will pass through one of the openings 16, then 100 between the partitions 14 and 15 into contact with the mercury, back again between the partitions 14 and the partitions 15 to an opening 16 and weave back and forth throughout the entire length of the circular 105 wall of the inner rotor 2 until it reaches the bottom of the outer rotor 1 where its speed will be accelerated by the impeller blades 8 to cause any particles of mercury which may have become mixed with the ore pulp 110

to separate by centrifugal action and be retained while the lighter sludge is discharged through the opening 6.

The outer rotor may be driven at one speed and the inner rotor at a different speed, or the inner rotor may be held stationary or rotated in a reverse direction. It is desirable that the outer rotor in any event rotate at a speed greater than the inner rotor because it is necessary to drive the outer rotor at considerable speed in order to maintain the wall 20 of mercury in the position shown in Fig. 1. If the speed of the outer rotor is too slow, the mercury will have a tendency to flow or gravitate to the bottom of the outer rotor and pass off with the sludge through the opening 6.

The inner rotor is provided with a plurality of radial vertical partitions 21, which are connected to the partitions 14 and 15 but which are in spaced relation with the wall of the inner rotor so that transverse ports 22 are provided for the passage of the material through the inner rotor or distributor.

From the foregoing it will be apparent that the material will be subjected to a plurality of contacts with the mercury so that the mercury will have time enough to take out the metal. The metal will be recovered from the mercury later in any appropriate manner.

In Fig. 2 I have shown a slightly modified form in which the outer rotor 23 conforms generically to the rotor in Fig. 1 except that it has spaced circular baffles 24 and 25 for the mercury, the baffles being provided with ports 26 and 27. The baffles 24 and 25 extend through the mercury column and have close clearance with the radial partitions 28 on the rotor 29. The material, therefore, will pass through the tortuous channel, as shown in Fig. 2.

In order to insure the mercury passing along at the same speed as the outer rotor, I may have recourse to the modification shown in Fig. 3 in which the outer rotor 29' is provided with vertical ribs 30, which will be embedded in the body of mercury so that it will have a tendency to carry the mercury along at the same speed as the wall of the outer rotor so that the essential scrubbing effect may be maintained by a rapidly moving sheet of mercury in contact with a slower moving body of ore pulp which is retarded by the inside member of the machine.

It will be apparent, therefore, that the sludge or pulp will be subjected to a plu-

rality of successive treatments by the mercury column because the sludge will pass in a tortuous path through the separator, coming into contact with the mercury from time to time until it finally reaches the bottom of the outer rotor, at which time it is assumed that the metal will have been removed.

What I claim and desire to secure by Letters-Patent is:

1. A separator comprising a hollow rotor, 70 and a distributor within it, the distributor having a circumferential wall provided with a plurality of ring-shaped partitions, the alternate ring-shaped partitions having ports, the ported partitions being wider 75 than those between them.

2. A separator comprising a rotor, a distributor within the rotor, ring-shaped partitions carried by the distributor, each alternate partition having openings therein, and vertical partitions in spaced relation with the wall of the distributor and connected to the first-named partitions.

3. A separator comprising a rotor and a distributor within the rotor, the distributor comprising a disk having a depending wall, ring-shaped partitions on the wall, and radial partitions carried by the distributor.

4. A separator comprising an outer rotor, an inner rotor constituting a distributor, the inner rotor comprising a disk having a depending wall, and ring-shaped partitions on the wall, alternate partitions being wider than those between them, the partitions being directed in planes at right angles to a 95 mercury chamber within the outer rotor.

5. A centrifugal separator comprising two concentric members, one of which is provided with means for supporting a column of mercury, there being a space between the 100 two members providing a separating chamber, one of said members having circumferential partitions extending across the separating chamber.

6. A centrifugal separator comprising two concentric members, one of which is provided with means for supporting a column of mercury, there being a space between the two members providing a separating chamber, one of said members having circumferential partitions extending across the separating chamber, the other of which has partitions alternating with the first partitions and also extending across the separating chamber.

In testimony whereof I affix my signature.

WILLIAM C. COLEMAN.
